(57) CLAIM

The ornamental design for watch-shaped toy, as shown and described.

DESCRIPTION

FIG. 1 is a perspective view of a watch-shaped toy;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines in the drawings are for the purpose of illustrating portions of a watch-shaped toy that form no part of the claim.
